US0D1110089S

(12) United States Design Patent (10) Patent No.: US D1,110,089 S
(45) Date of Patent: * Jan. 27, 2026

(54) PORTABLE CHAIR

(71) Applicant: YETI Coolers, LLC, Austin, TX (US)

(72) Inventors: Derek G. Sullivan, Austin, TX (US);
Andrew J. Winterhalter, Austin, TX (US);
John W. Dow, Austin, TX (US);
Donald Edward Desroches, Austin, TX (US)

(73) Assignee: YETI Coolers, LLC, Austin, TX (US)

() Term: 15 Years

(21) Appl. No.: 29/989,997

(22) Filed: Feb. 18, 2025

Related U.S. Application Data

(63) Continuation of application No. 29/978,627, filed on Dec. 13, 2024, now Pat. No. Des. 1,067,323, which is a continuation of application No. 29/935,953, filed on Apr. 4, 2024, now Pat. No. Des. 1,068,303, which is a continuation of application No. 29/842,720, filed on Jun. 15, 2022, now Pat. No. Des. 1,028,549, which is a continuation of application No. 29/804,131, filed on Aug. 18, 2021, now Pat. No. Des. 955,131, which is a continuation of application No. 29/770,887, filed on Feb. 17, 2021, now Pat. No. Des. 929,143, which is

(57) CLAIM

The ornamental design for a portable chair, as shown and described.

DESCRIPTION

FIG. 1 is a top, front, right perspective view of a portable chair showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown are included for the purpose of illustrating portions of the portable chair that form no part of the claimed design.

1 Claim, 7 Drawing Sheets

Related U.S. Application Data

a continuation of application No. 29/676,759, filed on Jan. 14, 2019, now Pat. No. Des. 911,731.
